UNITED STATES PATENT OFFICE.

HYMAN MAIMIN, OF NEW YORK, N. Y.

CLOTH-CUTTING MACHINE.

1,003,281.

Specification of Letters Patent. Patented Sept. 12, 1911.

Application filed May 20, 1911. Serial No. 628,407.

To all whom it may concern:

Be it known that I, HYMAN MAIMIN, citizen of the United States, residing in the city of New York, State of New York, have 5 invented certain new and useful Improvements in Cloth-Cutting Machines, of which the following is a full, clear, and exact description, reference being had to the accompanying drawings, forming a part of this 10 specification.

My invention relates to cloth-cutting machines and particularly to that type of such machines employing a vertically-reciprocating cutting blade usually driven through 15 suitable connecting actuating mechanism from the shaft of an electric motor mounted on the main frame. Such machines are well known, an example of the type being shown in U. S. patent to Ballard, No. 20 873,285 dated December 10, 1907. In such machines of that type, no means forming any part of the machine proper, have ever been provided for sharpening the cutting blade, though in such machines having a 25 rotating disk-shaped blade or cutter, primitive means have been utilized consisting of one or more grinding stones mounted in a frame hinged to some part of the mechanism adjacent thereto.

30 The object of my invention is to provide adequate knife-sharpening mechanism normally out of contact with the knife blade, including means to operatively support and actuate it, and means to shift it into and 35 out of operative position relatively to the knife blade, without stopping the machine and the actuation of its cutting blade.

To these ends my invention consists of certain novel elements in combination with 40 each other and with the frame of the machine and its adjunctive parts, including its presser-foot and its cutting blade and the supporting and actuating devices therefor; as hereinafter described in detail; the novel 45 and essential characteristics being recited in the several appended claims.

In the accompanying drawings, Figure 1 is a front elevation of my improvements, including enough of a known type of a cloth- 50 cutting machine to illustrate the application of my invention thereto. Fig. 2 is a side elevation thereof, and Fig. 3 a lateral section of the same, on line *a*—*a* of Fig. 2. Fig. 4 is a vertical section, partly in elevation, 55 of the blade-sharpening device, detached, the parts being in operative or down-

ward position and seen from one side, and Fig. 5 a like view of the same, looking from the front, and with the parts in elevated and inoperative position. Fig. 6 is a side elevation of the lower end of the sharpening device in operative position relatively to the cutting blade, the presser-foot in inoperative position; and Fig. 7 is a like view of the same, with the presser-foot in operative position, and the sharpening device in raised or inoperative position.

Referring now to said drawings: 1 indicates a portion of the main frame of the machine inclosing the motor (not shown) 70 which actuates, through appropriate connections, the vertically-reciprocating cutting blade.

2 is the particular portion of the frame, including the bracket 16 and the bearings 3 75 and 4 forming part of it, on which my improvement is mounted; 5 is the driving rod on the lower end of which the vertically-reciprocating cutting blade 6 is detachably mounted by the set-screw 7. The said driving rod is actuated by suitable connections 80 between it and the motor.

8 is the foot-plate from which the standard 9, forming part of the main frame, proceeds. The standard may have a groove, 85 indicated by the dotted line, in which the cutting blade is guided in its vertical reciprocation.

10 is the presser-foot, which is preferably made in the form shown in elevation in Figs. 90 2, 6 and 7 and illustrated in the section Fig. 3, so that it will, at its rearward part, embrace the edge of the cutting blade and consequently operate as a guard therefor, when in normal position, as in Fig. 7, and may 95 be swung free from the blade, as shown in Figs. 2 and 6 for the purpose of sharpening the blade.

Mounted fixedly on the lower end of the portion 2 of the main frame is a bracket 100 frame 16 having tubular bearings 3 and 4 at its top and bottom ends; and in a recess in the rear of the upper bearing 4 is let in a pinion 12 (see Fig. 2) carried on end of a short shaft 12^a actuated by hand wheel 12^b 105 (see Fig. 1) for the purpose of vertically adjusting the tubular shaft 19. Said shaft has such vertical adjusting movement imparted to it by means of a rack 18 formed on a rearward part of its periphery. Between 110 its bearings 3 and 4 the said shaft is preferably encircled by a spring 16, to give it

some reverse tension when said shaft is elevated, by the aforesaid rack and pinion, there being a ring 16^a fast on said shaft; and a ring nut 13 may be provided to fix-
5 edly hold said parts relatively.

The lower end of the tubular shaft 19 is slotted, as indicated at 21; the extreme end of the slot being narrowed, as indicated at 22 (Fig. 5) for the purpose to be described.
10 Mounted slidably in said tubular shaft 19 is a stem 20 which, in its lower half in length, is split to provide a pair of spring arms 23, or obviously the latter may be separately constructed and mounted in the end 15 of the solid portion of the stem 19 (see Fig. 4). These spring arms have an outwardly-extending tendency, as indicated in Fig. 5, so that when on the completion of their downward movement in the tubular shaft 20 19, reaching the narrowed portion 22 of the slot 21 in said shaft (see Fig. 5) they will be brought together as seen in Fig. 4. On the lower free end of each spring arm 23 is mounted a stub-shaft 28 on which is carried, preferably rotatably, a cylindrical grinding stone 26; and it is of some importance that these stub-shafts should be so, relatively to each other, that the two grinding stones will be in slightly different horizontal planes. In operative position, to sharpen the cutting blade, as indicated in Figs. 2 and 6, they will therefore sharpen adjacent but different sections of the blade on the two sides of its edge.
25 The presser-foot 10, as shown, is novel with me, in respect of its mounting and mode of operating resulting therefrom. To these ends it is carried by its yoke-like stem, through each member of which passes a pivot pin 27, which in turn passes through the wall of the tubular shaft 19. Mounted fast on this pin 27 is a sector 24 having two slots 24^a, 24^b, and mounted loose on the same pin is a spring-actuated finger 25
30 which engages one of said notches of the sector in the operative or normal position of the presser-foot (Fig. 7), and the other of said notches in the inoperative position thereof (Fig. 6) which latter is the operative position of the grinding stones relatively to the cutting blade, as seen in the last named figure. The sector and pivot pin aforesaid are actuated by contact with the spring arms 23, 23, on the terminus of their 35 downward movement. Mounted on the portion 2 of the main frame of the machine is a guiding bracket 11 through a hole in which passes the upper end of the actuating stem 20; and on the upper end of this 40 stem is an impact knob 22, while encircling the stem and resting on said bracket-bearing 11 is a coiled spring 21, shown in distended position in Fig. 1 and under compressed tension in Fig. 2; the function of 45 which is to restore the actuating stem and

the elements carried by it to normal upward position after each manual pressure on the impact knob.

The operation of the device is, briefly stated, as follows: The material to be cut is laid on the foot-plate. As it varied in thickness or depth, and the presser-foot is required to rest upon it during the operative reciprocation of the cutting blade, that end is accomplished by actuating the hand-wheel 12^b, causing the pinion 12 to act on the rack 18 on the wall of the tubular shaft 19, carrying the latter and its appendant presser-foot upward or downward as required. In that operative position of the presser-foot, relatively to the work, its rearward bifurcated portion 10^a embraces, but does not contact with, the edge of the reciprocating blade, and to that extent operates as a guard. This position of the several parts is shown in Figs. 1 and 7, and is their operative position during the actuation of the machine in cutting goods. To sharpen the cutting blade, either with or without stopping the actuation of the cutting blade, the stem 20 is depressed, by intermittent manual pressure on the impact knob 22, the first depression throwing the presser foot into the position shown in Figs. 2 and 6, the spring pin 25 dropping into the appropriate notch 24^a in the sector 24 and holding the presser-foot in inoperative position temporarily as shown, while each downward reciprocating movement of the spring-arms 23 in the slot 21, including its contracted end 22, compresses the spring arms and brings the grinding stones carried thereby into contact with the opposite sides of the cutting blade. If the machine is stopped, repeated manual impacts on the impact knob will give a sufficient and perfect grinding effect, particularly with the stones in adjacent but varying horizontal planes as shown; while if the machine is kept running, a single manual pressure on the impact knob will be sufficient. By my improvement I am not only able to provide means to perfectly sharpen the blade, but the mechanical adjuncts thereof are of such nature that they are utilized to support and actuate the presser-foot, both for operative and for inoperative positions.
50 Having thus described my invention, I claim as new and desire to secure by Letters Patent:—
1. In a cloth-cutting machine, the combination with the main frame and a cutting blade operatively mounted therein, of a tubular shaft mounted vertically adjustable in a plane in front of and adjacent to the vertical plane of the blade, a bearing for said shaft, a pair of grinding stones supported on each side of the blade and normally out of contact therewith, a pair of spring arms mounted slidably in said shaft

and carrying said stones, and means to reciprocate said spring arms and compress them toward each other on their downward reciprocatory movement.

5 2. In combination, in a cloth-cutting machine, a cutting blade, a bracket-bearing mounted on the main frame adjacent to the vertical plane of the cutting blade, a tubular shaft slotted at its lower end and mounted 10 in said bearing, means to vertically adjust said shaft in its bearing; a sliding stem mounted sleeve-like in said tubular shaft; a pair of spring arms carried by said sliding stem, and a pair of grinding stones carried 15 by said spring arms.

3. The combination, in a machine of the class recited, including its main frame and cutting blade, of a bracket bearing mounted on the front of said frame adjacent the 20 vertical plane of the blade, a tubular shaft slotted at its lower end mounted vertically adjustable in said bearing, a presser-foot pivotally supported adjacent the end of said shaft, a sliding stem mounted sleeve-like 25 therein, a pair of spring arms supported and actuated by said stem and adapted on their downward movement to swing the presser-foot on its pivotal bearing, a pair of grinding stones carried by said spring arms, and 30 means to compress said spring arms on their downward reciprocatory movement and bring the stones in operative contact with the blade.

4. In a machine of the class recited, the 35 combination with its main frame and cutting blade, a bracket comprising two bearing rings and mounted on said frame adjacent to the vertical plane of the cutting blade, a tubular shaft vertically adjustable in said 40 bearings, a tension device therefor operating between said bearing rings, a presser-foot pivotally connected to the lower end of said shaft, devices slidingly mounted in said tubular shaft, a pair of grinding stones rotatably mounted in varying horizontal 45 planes and carried by said sliding devices, for the purposes set forth.

5. In combination, in a cloth-cutting machine, a cutting blade, a foot-plate and a 50 standard rising therefrom, a bracket-bearing mounted thereon adjacent the vertical plane of the blade, a tubular shaft mounted vertically adjustable in said bearing, a presser-foot pivoted at the lower end of said tubular 55 shaft, a notched sector coacting therewith, a spring controlled pin governing the same, devices mounted to reciprocate in said tubular shaft and adapted, by contact with the hinged presser-foot, to swing it out of operative 60 position and hold it in such position during the sharpening of the cutting blade, and means to sharpen the blade.

6. In a cloth-cutting machine comprising 65 a cutting blade, a foot-plate and a standard rising therefrom, the combination therewith

of a bracket bearing mounted adjacent the vertical plane of the blade, a tubular shaft mounted vertically adjustable in said bearing, a presser-foot hinged to the lower end of said tubular shaft and having a slotted 70 rear portion adapted to embrace the blade edge as a guard, when in normal operative position, a stem mounted to reciprocate in said tubular shaft, means actuated by the downward movement of said stem, and operating by contact with said presser-foot to swing it out of normal position to clear the edge of the cutter blade, with means to sharpen the blade actuated by said stem and its adjuncts. 75

7. In a cloth-cutting machine, the combination with the main frame and a cutting device, of a vertically adjustable tubular shaft, slotted longitudinally, bearings supporting said shaft in a vertical plane adjacent the cutting device, a presser-foot hinged to the lower end of said shaft, and a notched spring-controlled sector governing said hinge; a stem mounted slidably in said shaft, resilient means to maintain said stem 80 normally in raised position, a pair of spring arms carried by said stem, a pair of grinding stones carried in spaced relation by the respective ends of said spring arms and adapted, on compression of said spring arms, 85 to be brought into operative contact with the opposite sides of the cutting edge of the blade. 90

8. The combination, in a cloth-cutting machine, with the main frame and a cutting blade, of a vertically-adjustable tubular shaft, slotted longitudinally, bearings therefor supported from the main frame, a stem mounted slidably in said shaft, a pair of spring arms carried by said stem, a pair of grinding stones mounted on the respective ends of said spring arms and in substantial parallelism with the opposite sides of the edge of the cutting blade and adapted, on compression of said spring 100 arms, to be brought into operative contact with the cutting blade. 105

9. In a cloth-cutting machine, the combination with its main frame and cutting device, of a pair of dependingly-mounted spring arms, a pair of grinding stones rotatably mounted on the free ends thereof, means operating to impart vertical movement to said elements and to maintain them normally in a plane above that of the cutting device and in parallel vertical planes alining with the opposite faces of the cutting device; means operating to automatically compress said spring arms on their downward reciprocatory movement to bring the grinding stones carried thereby into operative relation to the cutting device to be sharpened, and resilient means adapted to restore said last-mentioned elements to normal position. 110 115 120 125 130

10. In a cloth-cutting machine, the combination with the main frame and a cutting device, of a pair of dependingly-mounted spring arms of varying lengths, and a pair 5 of grinding stones rotatably mounted, in different planes, on their respective free ends; means to operatively support and impart vertical reciprocatory movement to said elements, means to compress said spring 10 arms on their downward reciprocatory movement to bring the stones against the opposite edges of the cutting device, in different planes, and resilient means to cause a return movement of said elements to normal 15 position and relation.

11. In a cloth-cutting machine, the combination with its main frame and cutting device, of a pair of dependingly-mounted spring arms of slightly varying lengths, a 20 pair of grinding stones rotatably mounted on the respective free ends of said arms, means to support said spring arms and grinding stones normally above the plane of the cutting device to impart vertical recip- 25 rotatory movement, and in vertical planes parallel with the opposite faces of the cutting device, and means to automatically compress said spring arms on their downward reciprocatory movement to bring the

grinding stones into rotative contact in dif- 30 ferent planes with the opposite faces of the edge of the cutting device.

12. In a cloth-cutting machine, the combination with its main frame and a cutting device, of a tubular shaft, a vertically-ad- 35 justable bearing therefor mounted on the frame, a stem adapted to reciprocate in said shaft, a pair of spring arms carried by said stem, a grinding stone on the free end of each spring arm, resilient means to sup- 40 port said elements above the plane of the cutting device and with said stones in parallel vertical planes adjacent to the path of travel of the blade edge thereof; said tubu- 45 lar shaft having a gradually narrowed longitudinal slot operating to compress said spring arms on their downward movement, to bring the grinding stones carried thereby into operative relation to the edge faces of the cutting device to be sharpened. 50

In testimony whereof, I have hereunto af- fixed my signature this sixth day of May A. D. 1911.

HYMAN MAIMIN.
